UNITED STATES PATENT OFFICE.

WILLIAM H. HARTLEY, OF MOUNT PLEASANT, MICHIGAN.

BLACKBOARD-ERASER.

No. 879,767.

Specification of Letters Patent.

Patented Feb. 18, 1908.

Application filed June 13, 1907. Serial No. 378,822.

To all whom it may concern:

Be it known that I, WILLIAM H. HARTLEY, a citizen of the United States of America, residing at Mount Pleasant, in the county of Isabella and State of Michigan, have invented new and useful Improvements in Blackboard-Erasers, of which the following is a specification.

This invention relates to blackboard erasers, and one of the principal objects of the same is to provide a device of this character which is practically self-cleaning, and in which a new cleaning surface is always presented to the blackboard whenever required.

Another object of the invention is to provide a self-cleaning blackboard eraser in which the cleaning bands are mounted upon rollers and sufficiently spaced apart and provided with means whereby the fine particles of chalk are removed from the surface of the bands and deposited into a receptacle within the eraser at each rotation of the erasing bands.

These and other objects may be attained by means of the construction illustrated in the accompanying drawing, in which:

Figure 1 is a plan view of the back portion of the blackboard eraser with the cover removed. Fig. 2 is an underside plan view of the cover. Fig. 3 is a side elevation of the eraser. Fig. 4 is a detail view of one end of the eraser. Fig. 5 is a transverse section of the same.

Referring to the drawing for a more particular description of my invention, the numeral 1 designates the body portion of the eraser consisting of a box-like receptacle having a bottom 2 and upwardly extending sides 3, preferably provided with curved ends 4 and 5. Mounted to rotate between the sides 3 at one end is a roller 6 journaled upon the ends of screws 7 passing through the sides 3 and into the roller 6. A roller 8 is journaled in the opposite ends of the sides 3 in a slot 9 in said sides, said roller provided with projecting bearings or trunnions 10 supported upon spiral springs 11 by means of which the roller 8 will yield to the action of the eraser. Placed within the receptacle 1 is an inner support provided with side flanges 12 which rest upon the inner wall of the bottom 2, said support having an upper wall 13 provided with a slot 14 which communicates with the interior of receptacle 1. Endless bands 15 of felt or other suitable erasing material are

mounted upon the rollers 6 and 8 at each side of the slot 14 and at opposite sides of the guide lugs 16. These guide lugs are located at the opposite ends of the slot 14 and serve to hold the endless bands 15 at opposite sides 60 of said slot.

A cover 17 is connected to the sides 3 of the eraser in any suitable manner, as by hinges 18, and provided with a suitable latch or fastener 19. On the under surface 65 of the cover 17 a series of inwardly projecting, oppositely disposed cleaner blades 20 are secured.

The operation of my invention may be briefly described as follows: The eraser may 70 be used for erasing crayon marks upon a blackboard by moving the same sidewise, and whenever a new surface is required an endwise movement of the eraser will bring a new erasing surface in position for use, and 75 as the endless erasing bands 15 pass the cleaning blades 20, the fine particles of chalk are removed from the bands and deposited through the slot 14 in the receptacle 1, where they may be discharged at any suitable time 80 by opening the cover 17.

From the foregoing it will be obvious that a blackboard eraser made in accordance with my invention is practically self-cleaning and provides for a clean erasing surface at any 85 time, and prevents fine particles of chalk from escape around the blackboard.

The device can be manufactured at slight cost, is comparatively simple in construction, and is efficient and convenient for its purpose. 90

Having thus described the invention, what I claim is:

1. A blackboard eraser comprising a box or receptacle, rollers journaled in said receptacle, endless bands of erasive material mounted on said rollers, and a cover for said receptacle provided with cleaning blades to bear upon the surface of the endless bands to remove the fine particles of chalk and 100 deposit them in said receptacle. 95

2. A blackboard eraser comprising a receptacle, rollers mounted in the receptacle, one of said rollers being mounted upon springs, endless erasive bands mounted on 105 said rollers, and a cover provided with means for removing the chalk from the bands.

3. A blackboard eraser comprising a box or receptacle, rollers mounted in said receptacle, endless bands mounted on said 110

rollers, a support for said bands provided with a slot, and a cover provided upon its under side with inwardly projecting, oppositely disposed cleaning blades, substantially as described.

4. In a blackboard eraser, the combination of a box or receptacle, endless erasive bands mounted to rotate upon the eraser, and means for cleaning said bands at one

point in their rotation, substantially as described. 10

In testimony whereof, I affix my signature in presence of two witnesses.

WILLIAM H. HARTLEY.
